THERMAL INSULATION

Frank A. Biederman, Chicago, Ill., assignor to
Paper Patents Company, Neenah, Wis., a cor-
poration of Wisconsin

Application May 16, 1932, Serial No. 611,623
Renewed November 2, 1935

8 Claims. (Cl. 154—44)

This invention relates to thermal insulation such as may be used in refrigerators.

The main objects of the invention are to provide thermal insulation material of high efficiency but low cost; to provide thermal insulation in unit or cell form which will be convenient to manufacture, handle and install; and in general, it is the object of the invention to provide an improved thermal insulation of the kind referred to.

Other objects and advantages of the invention will be understood by reference to the following specification and accompanying drawing in which a unit of thermal insulation embodying a preferred form of the invention is illustrated.

In the drawing:—

Fig. 1 is a perspective,

Figs. 2 and 3 are sections on the lines 2—2 and 3—3 respectively, of Fig. 1,
20 Fig. 4 is a section similar to Fig. 2, but illustrating a modified construction,

Fig. 5 is a fragmentary side elevation of still another modification, and

Fig. 6 is a section on the line 6—6 of Fig. 5.

Referring now to the drawing, and more particularly to Figs. 1, 2 and 3, the thermal insulation therein shown, in the form of a unitary cell or panel which embodies a filling or packing 10 of cellulosic material. The body 10 is surrounded by a tubular casing of suitable material such as cardboard, the casing having front and back walls 11 and 12 and side walls 13 and 14. The walls are bent to form a rectangular tube and at one corner, the adjacent walls, in this instance the walls 12 and 13, are joined through the agency of a lip or flap 15 formed integral with the side wall 13, the lip or flap 15 being adhesively or otherwise secured to the adjacent marginal portion of the wall 12.

The body 10 of cellulosic material and the tubular casing, are further enclosed in a wrapper 16 of paper or other suitable material which is preferably of an inherently water-proof nature or specially treated so as to be impervious to moisture.

The wrapper 16 is first wrapped around the tubular container and is of such a size that marginal portions as indicated at 17 will overlap on the back wall of the casing intermediate its width. The overlapping marginal portions of the wrapper are united to each other by suitable moisture-proof adhesive material, for example, asphaltum, which will effectively seal the joint between the wrapper margins to prevent the penetration of moisture through the joint. It is also preferred to seal the portions of the wrapper adjacent the joint 17 to the back wall of the casing by means of a coating of the selected adhesive material. By this means, the possibility of a leak developing is effectively minimized.

The wrapper is preferably of such a length that after the joint 17 has been formed, the wrapper will be in the form of a tube of greater length than the body 10 and tubular casing so that end portions of the wrapper will project beyond the said body and casing. Such projecting end portions of the tubular wrapper may then be folded over in any approved manner and be sealed to form an impervious end enclosure. In the present instance, it is contemplated that the end closure 10 will be formed by first folding over the projecting end portions 18 of the wrapper portion covering the front wall portion 11 of the tubular casing, thereafter folding the opposite side wall wrapper portions 19 and 20 inwardly over the 15 portion 18 and then completing the end enclosure by folding the opposite side wall portion 21 over the portions 18, 19, and 20. Between each overlapping end fold, a coating of adhesive material such as asphaltum is applied to form an impervious joint between the respective folds, and it is preferred to additionally apply a coating of the adhesive material over the exposed joints at the ends as indicated at 22 in Figs. 1 and 2. A similar exterior coating of adhesive material may be 25 applied to the joint 17 as indicated at 23 in Fig. 3.

The body or packing 10 of cellulose material is preferably in the form of an assembly of relatively superposed sheets of crepe paper of a thin, 30 cobwebby nature. A block of such superposed crepe paper sheets encloses an immense number of small air spaces or cells between the sheets, and such air spaces and the skin resistance of the sheets constitute a highly efficient insulator.

In addition to protecting the tubular cardboard casing and the enclosed insulating material from moisture by means of the water-proofed wrapper 16, the casing and the assembly cellulose sheets may also be treated in the process of manufacturing the raw material from which the elements are cut, or otherwise, to render them substantially non-absorbent or moisture repellent.

Units or panels as above described may be 45 placed in any desired position in the walls of a refrigerator or the like, and means may be provided for preventing settling or packing of the cellulose sheets within the container or casing.

For example, the assembly of cellulose sheets 50 forming the body 10 may be adhesively secured at their top ends to the inside of the end wall portion 18 through the agency of a coating of silicate of soda (water glass) or other suitable adhesive material, such as indicated at 24. When 55 the sheets are thus secured to the top end of the casing, the sheets are, in effect, suspended therefrom and hence can not settle within the casing to leave a void in the upper end of the casing. Since the weight of the respective sheets is but 60

a fraction of an ounce, no difficulty is experienced in producing an effective suspension of the sheets as described. If desired to more firmly anchor the sheets in place, water glass or like adhesive material may be applied between the ends or edges of the sheets entirely around the same and the adjacent inside walls of the casing, and such adhesive material may also be applied as indicated at 25 between the outermost sheets of 10 the body 10 and the front and back walls 11 and 12 of the casing. Adhesive material such as water glass is preferred for the purpose described for the reason that it is odorless and contains no material conducive to the growth of fungi.

15 In Fig. 4, an insulation panel embodying generally the same construction as that above described in connection with Figs. 1 to 3 inclusive is shown but in different form. The edges of the unit are shown beveled to fit into a refrigerator 20 door or like space. Also, in this modification, the ends of the cellulose sheets 10 are adhesively united to a cardboard or like end wall 26 which is provided as an integral part of the inner casing member instead of to the end wall portion 18 25 of the outer wrapper as in Fig. 2. The sheets 10 are preferably adhesively secured at both ends to the respective ends of the casing so that the panel may be inserted into place with either end up, thereby avoiding the necessity for special care 30 in positioning the unit. It is, of course, to be understood that panels for refrigerators are more often of an elongated rectangular form so that the panel can not be inserted with an unsecured edge of the sheets uppermost. It is also preferred 35 that the joint 17 of the wrapper be positioned on the outside of the unit so as to be away from the coldest side.

As shown in Figs. 5 and 6, the body 10 may 40 be anchored relative to the casing by means of stitches 27 which extend through the panel at spaced points. A single row of such stitches may be provided adjacent the top end of the panel, or several such rows may be provided near the top end, and if desired, such stitches may be extended through the panel at spaced points 45 throughout its entire area. When stitching is used for anchoring purposes, it is preferable that the impervious wrapper if used be applied after the stitching is completed so as to effectively 50 cover up the small openings formed in the casing incident to the stitching operation.

The described unit construction is preferably designed so that its outside dimension will correspond to the outside dimension of the space in which the unit is to fit so that the insulation panel will fit snugly in the space and effectively avoid the leaving of small air spaces which would constitute leaks. By reason of the inherent compressibility of the described construction, the panel may easily be made to fit very snugly in its receiving space. The outside impervious wrapper if used may conveniently be formed of paper treated with asphalt which renders it quite suitable to the indicated purpose.

Changes in the described construction may be made without departing from the spirit of the invention, the scope of which should be determined by reference to the following claims, the same being construed as broadly as possible, consistent with the state of the art.

I claim as my invention:—

1. A thermal insulating unit comprising an assembly of superposed creped tissue paper sheets which are of such thinness as to be not self-supporting, and a casing enclosing the assembly, the sheets being suspended edgewise from the top wall of the casing.

2. A thermal insulating unit comprising a casing, and an assembly of superposed creped tissue paper sheets forming a pad within the casing, an 10 edge portion of the assembly being adhesively secured to the inner side of the casing.

3. A thermal insulating unit comprising a casing, and an assembly of superposed creped tissue paper sheets forming a pad within the casing, 15 and peripheral edges of the assembly being adhesively secured to inner walls of the casing.

4. A thermal insulating unit comprising a casing, and an assembly of superposed creped tissue paper sheets forming a pad within the casing, the 20 outermost sheets having their outer surfaces adhesively secured to the respective adjacent inner sides of the casing, and the peripheral edges of the assembly being adhesively secured to adjacent 25 inner sides of the casing.

5. Thermal insulation comprising a soft and flexible bat formed of a multiplicity of superposed sheets of very thin, cobwebby, creped tissue paper, the bat embodying a multiplicity of small irregularly shaped and irregularly arranged cells 30 formed by the creping and openings in the sheets, said cells constituting dead air cells and being separated by the slight thickness of the tissue paper, the bat being of very light weight considering its bulk and having a low thermal conducting 35 capacity incident to its enclosure of dead air cells and the inherently low conductivity of such thin, cobwebby paper.

6. An insulating bat according to claim 5 and 40 provided with a relatively stiff protective covering means around at least a portion of the edges thereof.

7. Thermal insulation comprising a soft and flexible bat which is generally rectangular in cross section and which comprises a multiplicity 45 of superposed, relatively flat sheets of very thin, cobwebby, creped, cellulosic tissue, the bat embodying a multiplicity of small, irregularly shaped and irregularly arranged cells formed by the creping and openings in the sheets, said cells constituting dead air cells and being separated by the slight thickness of the sheets, the bat being 50 of very light weight considering its bulk and having a low thermal conducting capacity incident to its enclosure of dead air cells and the inherent low conductivity of said thin cobwebby sheets, and a relatively stiff protective covering or edging for said bat, the adjacent edges of said sheets being adhesively attached to the said protective covering or edging.

8. A thermal insulating unit comprising a relatively stiff supporting means formed of sheet cellulosic material, and a multiplicity of superposed, relatively flat sheets of very thin, cobwebby, creped, cellulosic tissue which are of such thinness as to be not self supporting, and means for anchoring said sheets to said relatively stiff supporting means in order that said thin sheets shall be supported thereby during use of said unit.

FRANK A. BIEDERMAN. 70
